[57] CLAIM

The ornamental design for a tire for a vehicle wheel, as
shown and described.

DESCRIPTION

FIG. 1 is a perspective view of a tire for a vehicle wheel showing my new design it being understood that the tread design is repeated throughout the circumference of the tire, the opposite side being substantially the same as that shown;

FIG. 2 is a front elevational view thereof;
FIG. 3 is a side elevational view thereof.

FIG. 1

FIG. 2

FIG. 3
